UNITED STATES PATENT OFFICE.

CALVIN B. ROE, OF MOUNDSVILLE, WEST VIRGINIA, ASSIGNOR TO FOSTORIA GLASS COMPANY, OF MOUNDSVILLE, WEST VIRGINIA, A CORPORATION OF WEST VIRGINIA.

DESIGN FOR A COMBINED CANDLE HOLDER AND BOBACHE.

Application filed December 21, 1922. Serial No. 4,653. Term of patent 14 years.

To all whom it may concern:

Be it known that I, CALVIN B. ROE, a citizen of the United States of America, and resident of Moundsville, county of Marshall, and State of West Virginia, have invented a new, original, and ornamental Design for a Combined Candle Holder and Bobache, of which the following is a specification, reference being had to the accompanying drawings, in which—

Figure 1 is a top plan view of a combined candle holder and bobache, showing my new design; and—

Figure 2 is a side elevation of the same.

I claim:

The ornamental design for a combined candle holder and bobache, as shown.

CALVIN B. ROE.
